RECORDING AND REPRODUCING
PHONOGRAPHEmmor V. Schneider, Alliance, Ohio, assignor to
Alliance Manufacturing Company, Alliance,
Ohio, a corporation of Ohio

Application September 11, 1940, Serial No. 356,313

5 Claims. (Cl. 274—13)

The invention relates to phonographs and more particularly to a phonograph having a combination recording and play-back arm.

There is at present a considerable demand for combination recording and play-back phonographs for home use as a large number of people have become interested in making their own records and playing the same as well as playing the usual commercial records.

This demand has produced considerable business in the manufacture of combination instruments provided with one arm for carrying the cutting or recording needle with suitable tension and screw feeding means thereon for properly spacing the grooves and sound track and a second arm for carrying the play-back needle by means of which the sound from the phonograph records may be reproduced.

The object of the present improvement is to provide a phonograph having a single arm adapted to carry either a substantially vertical recording needle or an inclined play-back needle and having a novel screw feeding and tension means for properly spacing the grooves or sound track when used for recording and means for releasing the same when the arm is to be used to play back the records.

Another object is to provide a novel friction drive for moving the arm when recording.

A still further object is the provision of an improved spring hinge device for mounting the reproducer in the pick up arm.

Another object is the provision of novel tension means for holding the pick up arm in operative and inoperative position.

The above objects together with others which will be apparent from the drawings and following description may be attained by constructing the improved phonograph in the manner illustrated in the accompanying drawings in which

Figure 1 is a bottom plan view of the improved phonograph mechanism;

Fig. 2, a longitudinal sectional view through the same taken on the line 2—2, Figure 1;

Fig. 3, an enlarged longitudinal sectional view through the pick up arm;

Fig. 4, an enlarged fragmentary elevation of the improved spring hinge means for the pick up arm;

Fig. 5, a bottom plan view of the same; and

Fig. 6, a fragmentary sectional view of the friction drive means for the pick up arm and the releasing mechanism therefor taken on the line 6—6, Fig. 2.

Similar numerals refer to similar parts throughout the several views.

The platform of a phonograph cabinet is indicated generally at 10 and the spindle 11 for the turntable 12 is journaled through said platform and mounted in a suitable bearing bracket 13 connected to the under side of the platform as by screws 14.

As in usual practice the turntable may have the depending peripheral flange 15 the inner side of which is engaged by the friction tire 16 upon the wheel 17 which may be journaled upon a post 18 mounted upon the slidable plate 19.

The friction tire 16 upon the wheel 17 also engages the pulley 20 upon the upper end of the shaft 21 of a motor 22 by means of which the wheel 17 is driven by the motor and in turn drives the turntable at the desired speed.

The motor may be suspended as by the rods 20 23 from a base plate 24 secured to the under side of the platform 10 as by the rubber grommets 25.

The slidable plate 19 carrying the post 18 for the wheel 17 is slidably mounted upon the upper side of the base plate 24 and operates within an opening 26 in the platform 10.

The motor mounting itself forms no part of the present invention and no further explanation thereof is thought necessary.

30 The low portion of the turntable spindle 11 has a worm screw 27 thereon meshing with the worm wheel 28 mounted upon a shaft 29 journaled transversely through the bearing bracket 13, the outer end of said shaft forming a friction pulley 30.

The pick up arm indicated generally at 31 is mounted in a manner to be later described upon the shaft 32 journaled in a bearing 33 fixed upon the platform 10.

40 The shaft 32 extends some distance below the platform and has fixed thereto the hub 34 of a rocker arm 35 upon the free end of which is formed an arcuate segment 36 preferably having a strip of rubber or other friction material 37 attached thereto for contact with the friction pulley 30.

One end of the segment 36 is turned down as at 38 forming a stop for contact with the pulley 30 to limit movement of the arm in one direction.

50 The other end of the segment is turned down at 39 to limit movement of the arm in that direction and a cut out 40 is provided in the periphery of the segment for a purpose to be later described.

In order to cooperate with the friction roller 60 39 to frictionally drive the segment 36 of the

rocker arm 35 in order to move the pick up arm 31 across the face of the record, when cutting or recording, a roller 41 is provided to bear against the opposite side of the segment 36 from that contacting the friction roller 30, so as to hold the friction surface 37 of the segment in contact with the friction roller 30.

This roller 41 is loosely journaled upon a spindle 42 carried by one arm 43 of a bell crank lever pivoted as at 44 upon the bearing bracket 13, the other arm 45 of the bell crank lever having a spring 46 connected thereto and to a stationary portion of the device, such as the bearing bracket 13 in order to normally hold the roller 41 upon the segment 36 and force the same into frictional contact with the friction roller 30.

For the purpose of releasing the friction contact upon the segment 36 when it is desired to play back a record a link 47 is pivoted at one end to the free end of the bell crank arm 45, as indicated at 48, the other end of said link being pivoted as at 49 to the free end of the arm 50 of a bell crank pivoted as at 51 upon the platform 16.

The other arm 52 of this bell crank has a link 53 pivoted to its free end as at 54, the other end of the link 53 being pivoted as at 55 to a lever 56 pivoted as at 57 having an off set portion located through an arcuate slot 58.

By throwing the lever 56 from the full line position to the broken line position shown in Fig. 1, the link 53 is thrown over the center 57 and through the linkage and leverage above described, the roller 41 is raised from contact with the segment 36 and held in this position.

Another feature of the invention is the manner in which the reproducer 59 is mounted upon the pick up arm 31.

As best shown in Fig. 3 this pick up arm is hollow and the reproducer is mounted within the open lower side of the pick up arm.

For this purpose a brass or bronze strip 60 is riveted at one end to the adjacent end of the reproducer 59 as indicated at 61 and the brass or bronze strip is located between two metal clamping plates 62 having knife edges 63 bearing against opposite sides of the flexible strip 60 at a point spaced from the adjacent end of the reproducer.

The flexible strip 60 and clamp plates 62 are connected at their other ends to the depending posts 64, in the pick up arm, as by screws 65.

With this construction the flexible strip 60 will hinge at the point where the knife edges 63 contact the same and as the clamping plates 62 are outwardly curved adjacent to the knife edge portions, as shown at 66, the flexible strip 60 will have freedom of movement between the same as the strip is flexed.

A pull spring 67 is connected at one end to an ear 68 at the hinged end of the reproducer, the other end of said spring being connected to a nut 69 upon an adjusting screw 70 located through the depending wall 71 of the recessed portion 72 in the pick up arm.

With this construction the tension upon the spring 67 may be adjusted as desired.

The usual flexible electric cord 13 leads to the reproducer 59.

The reproducer 59 is readily a combination reproducer and recorder and for this purpose is provided with a substantially vertical socket 74 to receive a recording or cutting needle 75 when the device is used for cutting or recording a record and with an inclined socket 76 to receive

a play back needle 77 when the device is being used to play back a record.

The usual set screws 78 are provided for clamping the needles in the sockets and for this purpose vertical slots 79 are formed in the depending end wall 80 of the pick up arm to permit the required vertical movement of the reproducer upon its hinge.

For the purpose of mounting the pick up arm upon the oscillating post 32 a channel shaped bracket 83 is fixed upon the upper end of the post 32 and provided at its outer end with notches 84 to receive the headed studs 85 upon the depending side walls 86 of the pick up arm.

A pull spring 87 is connected at one end to a stud 88 at the upper rear end of the pick up arm and at its other end to a stud 89 on the bottom of the channel bracket 83 at the forward or inner end thereof.

An adjustable stop screw 90 depends from the pick up arm and is arranged to contact the ear 91 at the forward or inner end of the channel bracket 83 when the pick up arm is in operative position.

When it is desired to raise the pick up arm from the record it is swung upwardly upon the pivot points 85 to the broken line position shown in Fig. 3, the spring 87 throwing over center and holding the pick up arm in raised position until it is again manually moved to operative position.

In operating the device for recording or cutting a record, a cutting needle 75 is clamped in the vertical socket 74 of the pick up arm and the lever 56 is thrown to the full line position shown in Fig. 1 permitting the spring 46 to hold the roller 41 tightly against the upper surface of the segment 36 forcing the friction surface 37 thereof into frictional contact with the friction roller 30.

A blank record to be cut is placed upon the turntable 12, the motor 22 is started and the pick up arm lowered upon the record near the periphery thereof.

The turntable will be rotated at proper speed through the friction drive from the motor and through the worm and gear drive from the turntable spindle, the friction roller 30 will be driven at proper speed to frictionally drive the arm 35 moving the pick up arm at the desired speed to properly form the sound track upon the record.

As the pick up arm moves to the center of the record the roller 41 will drop into the notch 40 preventing further movement of the pick up arm.

When it is desired to use the device for play back of a record, the lever 56 is thrown to the broken line position shown in Fig. 1 raising the roller 41 out of contact with the segment 36 so that the pick up arm is free to move as the reproducing or play back needle 77 rides through the sound track of the record.

I claim:

1. A phonograph including a turntable, a pick up arm oscillatably mounted at its rear end on a vertical pivot for movement across the turntable, and feed mechanism located immediately beneath the turntable, said feed mechanism including a friction pulley, gearing connecting the turntable and friction pulley for rotating the pulley, a segment extending rearwardly from and moved by said friction pulley, the rear end of said segment being rigidly connected to the vertical pivot of the arm for simultaneous horizontal movement with the arm, pressure means for bearing against one side of the segment and pressing the other side thereof into frictional contact with the friction pulley for moving the

pick up arm at the proper speed to cut a sound track upon a record on the turntable, and means for releasing said pressure means so that the pick up arm may swing freely upon its vertical pivot.

2. A phonograph including a turntable, a pick up arm oscillatably mounted at its rear end on a vertical pivot for movement across the turntable, and feed mechanism located immediately beneath the turntable, said feed mechanism including a friction pulley, gearing connecting the turntable and friction pulley for rotating the pulley, a segment extending rearwardly from and moved by said friction pulley, the rear end of said segment being rigidly connected to the vertical pivot of the arm for simultaneous horizontal movement with the arm, pressure means for bearing against one side of the segment and pressing the other side thereof into frictional contact with the friction pulley for moving the pick up arm at the proper speed to cut a sound track upon a record on the turntable, and means for releasing said pressure means so that the pick up arm may swing freely upon its vertical pivot, and a horizontal pivot connecting the pick up arm to the vertical pivot so that the pick up arm may be raised and lowered independently of the segment.

3. A phonograph including a turntable, a pick up arm oscillatably mounted at its rear end on a vertical pivot for movement across the turntable, and feed mechanism located immediately beneath the turntable, said feed mechanism including a friction pulley, gearing connecting the turntable and friction pulley for rotating the pulley, a segment extending rearwardly from and moved by said friction pulley, the rear end of said segment being rigidly connected to the vertical pivot of the arm for simultaneous horizontal movement with the arm, a pressure roller for bearing against one side of the segment and pressing the other side thereof into frictional contact with the friction pulley for moving the pick up arm at the proper speed to cut a sound track upon a record on the turntable, and means for releasing said pressure roller so that the pick up arm may swing freely upon its vertical pivot.

4. A phonograph including a turntable, a pick

up arm oscillatably mounted at its rear end on a vertical pivot for movement across the turntable, and feed mechanism located immediately beneath the turntable, said feed mechanism including a friction pulley, gearing connecting the turntable and friction pulley for rotating the pulley, a segment extending rearwardly from and moved by the friction pulley, the rear end of said segment being rigidly connected to the vertical pivot of the arm for simultaneous horizontal movement with the arm, a lever pivoted adjacent to the segment, a roller upon the lever, spring means associated with the lever for pressing the roller against the segment and holding the segment in frictional contact with the friction pulley for moving the pick up arm at the proper speed to cut a sound track on a record on the turntable, and means operatively associated with the lever for moving the roller away from the segment so that the pick up arm may swing freely upon its vertical pivot.

5. A phonograph including a turntable, a pick up arm oscillatably mounted at its rear end on a vertical pivot for movement across the turntable, and feed mechanism located immediately beneath the turntable, said feed mechanism including a friction pulley, gearing connecting the turntable and friction pulley for rotating the pulley, a segment extending rearwardly from and moved by the friction pulley, the rear end of said segment being rigidly connected to the vertical pivot of the arm for simultaneous horizontal movement with the arm, a lever pivoted adjacent to the segment, a roller upon the lever, spring means associated with the lever for pressing the roller against the segment and holding the segment in frictional contact with the friction pulley for moving the pick up arm at the proper speed to cut a sound track on a record on the turntable, and means operatively associated with the lever for moving the roller away from the segment so that the pick up arm may swing freely upon its vertical pivot, and a horizontal pivot connecting the pick up arm to the vertical pivot so that the pick up arm may be raised and lowered independently of the segment.

EMMOR V. SCHNEIDER.
